UNITED STATES PATENT OFFICE.

CHARLES DOERING, JR., AND HENRY H. DOERING, OF CHICAGO, ILLINOIS.

DEVICE FOR DISPENSING LIQUIDS.

1,240,830.

Specification of Letters Patent. Patented Sept. 25, 1917.

Application filed June 21, 1915. Serial No. 35,193.

To all whom it may concern:

Be it known that we, CHARLES DOERING, Jr., and HENRY H. DOERING, citizens of the United States, and residents of Chicago, in 5 the county of Cook and State of Illinois, have invented certain new and useful Improvements in Devices for Dispensing Liquids, of which the following is a description, reference being had to the accompanying drawings, which form a part of our specification.

Our invention relates to a device adapted to dispense liquid in predetermined quantities from a suitable container or bottle, without the necessity of constantly handling the container or bottle; and, at the same time, permitting the liquid to be sold or dispensed in predetermined uniform quantities in a rapid manner.

20 A further object of our invention is to provide a device of the character herein specified wherein the quantity to be dispensed may be readily varied, either increased or diminished, by suitable mechanism, the regulations or "setting" whereof results in a uniform quantity being dispensed at each adjusted position of said mechanism, as will be more fully understood from the following specification.

30 The advantages above specified and others inherent in the construction will be readily apparent from the following detailed description.

In the drawings:

35 Figure 1 is a side elevation of our device. Fig. 2 is a front elevation thereof on a smaller scale and shown provided with a liquid-container or bottle inverted into place.

40 Fig. 3 is an enlarged vertical sectional view, taken on the line 3—3 of Fig. 2, looking in the direction of the arrows.

Fig. 4 is a detail perspective view of the liquid-measuring valve.

45 Fig. 5 is a vertical sectional view, taken on the line 5—5 of Fig. 3, and looking in the direction of the arrows.

Fig. 6 is a partial longitudinal section and side view of a portion of the liquid-regulating mechanism.

50 In the particular exemplification of our invention, we illustrate the device provided with a suitable standard or pedestal 10, of any suitable cross-sectional contour and provided with a suitable base-portion 11, whereby the device will be given proper support and may also be permanently secured in

place. The upper portion of the standard or pedestal 10 is provided with a port 12, see Fig. 3, which extends to the outside of the pedestal or standard 10, and also communicates with the transversely disposed chamber 13, which is preferably shown cone shaped, see Fig. 3, although the chamber may be made of uniform dimensions throughout. The chamber 13 is open at both ends and receives the hollow conical valve 15, which is open at one end, namely the small or reduced end of the valve. The valve 15 is adapted to fit within the chamber 13 and permit the cap-portion 16^a of an elongated regulating member 16, to screw into the end of the chamber 13, while the elongated portion extends into the open-ended valve 15, as shown in Fig. 3; the regulating member 16 being shown in detail and longitudinal section in Fig. 6. One end of the chamber, to wit the larger end, is arranged to receive a cap 14, which is adapted to screw onto the end wall of the chamber, as shown in Fig. 3.

55 The general construction of valve 15 is shown very clearly in Fig. 4, where it will be seen that the cylindrical wall is provided with a pair of ports 17 and 18 arranged at a predetermined distance apart, so as to be alternately brought into register with the port 12 and the upwardly presented port 19, shown in Fig. 3; the latter port extends upwardly from the chamber 13 and communicates with the chamber or bottle-holding portion 20 of the device.

60 As shown in Figs. 3 and 4, the valve 15 has one end closed, as shown at 15^a in Fig. 4; the smaller or opposite end being open, as previously stated, to receive the regulating member 16. The valve 15 also has its circumferential wall provided at a predetermined point, with the arcuate port 21, see Figs. 3 and 4, which is of a length sufficient to constantly permit the port 21, during rotation of the valve 15, to be in register with the upwardly presented air-port 22, which extends through the upper portion of the standard or body of the device and communicates with the chamber or bottle-holding portion 20, see Fig. 3.

65 The circumferential wall of valve 15 is preferably extended beyond the end wall 15^a, as shown in Fig. 4, and a segment of the extended portion is cut-away so as to provide the shoulders 15^b at points substantially in the same longitudinal plane as the ports

17 and 18. The cut-away portion of the extended wall is adapted to receive a lug or pin 23, see Fig. 5, secured to or made integral with the inner periphery of the chamber 13, so as to extend into the cut-away portion of the extended wall of the valve, so as to engage the shoulders 15^a, 15^b during rotation of the valve, and thereby limit the movement of the valve, and insure registration of the port 17 and port 12 and registration of port 18 with port 19 when the valve is rotated to its fullest extent in either direction, as is clearly evident from the construction.

15 The end wall 15^a of the valve 15 is also provided with a spindle 24, preferably integral therewith, which extends through the cap or closure member 14, and has its outer end provided with a suitable operating handle 25, which may be removably secured in place by any suitable means.

The receptacle holding-portion 20 is preferably in the nature of an elongated tubular member, as shown in Fig. 3, with the upper end preferably flared so as to adapt it more especially to the contour or neck of a bottle, as shown at 26; the bottle being intended to be placed in an inverted condition in the holding-member 20, and maintained in the perpendicular position shown in the drawings. The elongated holding-portion 20 is of such transverse dimension as to provide a suitable air-chamber adapted to be placed in communication with both the bottle 26 and the valve 15, for the purpose of insuring the flow of the liquid from the bottle into the valve and from the latter out through the port 12, from whence it will be discharged by means of the spout 27 into a suitable cup or vessel.

In order to provide a cushion for the end or mouth of the bottle, so as not to injure the same, and, if desired, at the same time maintain the bottle slightly away from the wall of the holding-portion 20 at the upper flared end thereof, we show the bottom of holding-portion 20 provided with a washer or member 28, preferably of rubber or the like, upon which the mouth of the bottle may rest, as shown in Fig. 3; the member or washer 28 being so arranged, however, as not to interfere with the ports or passages 19 and 22.

The port 19 is preferably provided with the extended portion or tubular member 29, intended to extend into the mouth of the inverted bottle. The upper end is preferably provided with extended converging prongs 29^a so as to produce elongated slots, as shown at 30, to permit the flow of liquid, as well as the passage of air, into the bottle.

The construction of the tubular member 29, as described, will prevent the possibility of foreign matter, such as large portions of cork and the like seating itself on the end

of the member 29 where it would interfere with a proper flow of the liquid from the bottle.

The port 22 is also preferably provided with a tube 31 adapted to extend to a point 70 somewhat above the mouth of the bottle, as shown in Fig. 3, so that any slight spilling of liquid in holder 20 will not interfere with the movement of air into and out of valve 16 during the operation thereof.

In order to maintain the valve 16 in proper position within the valve-chamber and take up any wear, we provide a spring 32 adapted to press against the end wall 15^a of the valve 15 and against the cap or closure-member 14; the ports in the valve being made slightly larger than the ports in the standard or chamber, so that slight longitudinal movement of the valve, due to wear, may be had without interfering with the proper registration of the ports.

The regulating member or device 16, preferably consists of the elongated tubular portion, as shown in Fig. 6. The member is preferably internally threaded to receive 90 the diaphragm or member 33, which is adapted to be screwed lengthwise of the tubular portion of member 16, so as to regulate the extent to which the liquid may enter the tubular member 16. The outer 95 end of tubular member 16 is preferably formed in the nature of a cap-portion 16^a which screws into the end of the chamber 13, as previously described.

It is apparent from the construction that 100 when the diaphragm member 33 is moved lengthwise of member 16, the liquid-receiving space or chamber within valve 15 will either be increased or diminished, depending upon the direction in which diaphragm 105 member 33 is moved. For example, if diaphragm member 33 be moved to the extreme inner or right-hand end of member 16, the valve will have greater capacity than would be the case if the member 33 was left at the 110 point indicated in Fig. 6, so that each operation of the valve will dispense its maximum quantity of liquid. On the other hand, if diaphragm 33 is screwed to the extreme outer or left-hand end of tubular member 115 16, the compartment or liquid-receiving space within the tubular member, as well as that of the valve, will to that extent be lessened or shortened, so that a lesser quantity of liquid will be dispensed with each 120 operation of the valve.

In the operation of our dispensing device, the liquid-container or bottle 26 is inserted in the barrel or receiving-portion 20 in an inverted manner, as shown in the drawings, 125 the mouth of the bottle resting upon the cushioning means or washer 28. Except for the quantity of liquid which may spill during the insertion of the bottle, none of the liquid will flow into container 20, be- 130

cause the mouth of the bottle is flush with the washer or member 28 and air cannot pass into the bottle except through the valve 15. In view of the fact that a small quantity of liquid will spill into the holder-portion 20, we prefer to extend the air-tube 31, as shown in Fig. 3, so as to prevent the latter being sealed by the spilled liquid within holder 20. The manipulator will then rotate valve 15 into the position shown in Fig. 3, so as to bring port 18 into register with passage or port 19, and thereby establish communication with the interior of the bottle or container 26 by means of the extension or tube 29. The arcuate port 21 will also establish communication between the interior of valve 15 and the air-space or chamber within holder 20 by means of tube 31 and port or passage 22. With the valve in this position, air from within valve 15 will pass upward through port or passage 19 and tubular member 29 into the bottle, thereby allowing the liquid to flow from the bottle into valve 15. The liquid flowing into valve 15 will force surplus air out of the valve 15 through port 22, until the liquid has filled the liquid-receiving space of valve 15, and closed port or passage 22. As soon as the air-port or passage 22 has been sealed by the liquid, further flow of liquid from the bottle will be prevented, because of the inability of a further quantity of air entering the bottle or container 26. The construction of tubular member 29 is such that any extraneous matter, within the bottle or container 26 of such dimensions as would affect the valve, will be prevented from passing through tubular member 29; at the same time the construction of the tubular member will cause large air-bubbles passing upward to become broken or finely divided, thereby not only causing a better action of the device, but also more thoroughly aerating the liquid. When the valve 15 is filled, the manipulator will rotate the valve so as to bring port 17 into register with port or passage 12, at which time port 18 will be moved out of register with port or passage 19, thus preventing any further liquid entering the valve during the withdrawal of the liquid from the valve. By reason of the elongation of port 21, constant communication with air-port or passage 22 will be maintained during rotation of the valve to bring port 17 into register with port or passage 12. The admission of air will, of course, permit the liquid to flow out of valve 15 through port or passage 12 and be discharged through spout 27. The shoulders 15^b, in the cylindrical wall of valve 15, are arranged apart a distance corresponding with the distance between ports 17 and 18, so that the lug or shoulder 23, arranged within the chamber 13, will prevent too great a rotation of valve 15. It is evident

from the construction shown and described that a uniform quantity of liquid will be given with each operation of the valve. The quantity can be increased or diminished by positioning diaphragm member 33 to the desired point, so that the quantity dispensed will not be controlled by or at the will of the operator.

We have shown and described what we believe to be the simplest and best form of our invention, but the same may be altered in certain respects without, however, departing from the spirit of our invention, and we do not wish to be understood, therefore, as limiting ourselves to the exact construction shown and described.

What we claim is:—

1. A device for dispensing liquids, comprising a standard provided with a portion adapted to hold a liquid container or bottle in inverted position and to provide an air chamber, a chamber provided with an inlet port and air port arranged in communication with the holding portion and with a discharge port in the bottom thereof, a hollow cylindrical valve provided with an open end and with ports arranged to alternately register with the inlet port and discharge port of said chamber when the valve is rotated a predetermined distance and with an elongated port adapted to constantly register with the air port, and means arranged at the open end of said valve and extending into said valve, said means being provided with an adjustable portion whereby the holding capacity of said chamber may be regulated.

2. A device for dispensing liquids, comprising a standard provided with a portion adapted to hold a liquid container or bottle in inverted position, a chamber beneath said bottle-holding portion having an inlet port and an air port both in communication with the holding-portion, and with an outlet port, a hollow elongated valve rotatably mounted in said chamber provided with inlet and outlet ports at separated points and an air inlet arranged to constantly register with the air port in the chamber, said air port being adapted to be sealed by the inflowing liquid and thereby automatically prevent further flow into said valve, and means extending into said valve for determining the capacity of said valve and adapted to close the end of said chamber and said valve.

3. A device for dispensing liquids, comprising a standard provided with a portion adapted to hold a liquid container or bottle in inverted position and to provide an air chamber, a chamber arranged beneath the bottle-holding portion having an inlet port and air port communicating with said holding-portion and having a discharge port, a hollow valve rotatably mounted in said chamber and provided with ports at prede-

terminated points adapted to be alternately brought into register with the inlet port and discharge port of said chamber and having an elongated port extending circumferentially of the valve and adapted to constantly register with said air port, a closure member for the end of said chamber and adjacent end of the valve provided with a tubular portion arranged to extend into the hollow valve, and means adjustably mounted in said tubular portion and accessible from the inner end of said portion whereby the capacity of the valve may be determined.

4. A device for dispensing liquids, comprising a standard provided with a portion adapted to hold a liquid container or bottle in inverted position and to provide an air chamber, a chamber provided with an inlet port and air port arranged in communication with the holding-portion and provided with a discharge port, an open ended hollow valve provided with ports adapted to register with the ports of said chamber, the ports being so arranged as to alternately register with the inlet and discharge ports of the chamber without affecting the air port, and closure means arranged at one end of the chamber and having an internally threaded tubular portion extending into said valve, said tubular portion being provided with a diaphragm having a threaded perimeter and accessible only from the inner end of said tubular portion whereby the holding capacity of the valve may be regulated.

5. A device for dispensing liquids, comprising a standard having a portion adapted to hold a liquid container or bottle in inverted position and to provide an air chamber, the lower part of the standard being provided with a cylindrical open-ended chamber having ports communicating with said bottle-holding portion and an outlet port, an elongated hollow valve rotatably mounted in said chamber and provided with a pair of ports adapted to alternately be brought into register with the outlet port in the chamber and one of the ports thereof communicating with the bottle-holding portion, said valve being also provided with an elongated port adapted to constantly register with the other port of the chamber communicating with the air chamber in the standard, and closure means for the open end of said cylindrical chamber and the valve, said means having an extension taking into the valve and provided with a regulable portion whereby the capacity of the valve may be determined.

6. A device for dispensing liquids, comprising a standard provided with a container or bottle-holding portion adapted to

also provide an air chamber, an open-ended chamber located beneath said portion and having passages communicating with the holding-portion, one passage being provided with an extension adapted to enter the neck of a bottle and constitute a liquid inlet, while the other passage has a conduit extending to a point above the liquid-conveying extension adapted to constitute an air conduit and a third passage constituting a discharge, a cylindrical valve rotatably mounted in said chamber, provided with ports at prearranged points, two of which are adapted to alternately register with the inlet and discharge passages in said chamber, while the other port is elongated in a circumferential direction and is adapted to constantly register with the air passage of the chamber, one end of said valve being formed to provide stops whereby the extent of rotation of the valve is determined, a closure member for the end of said chamber and said valve, said member being provided with a tubular portion extending into said valve, and means adjustable lengthwise of said tubular portion whereby the capacity of said valve may be regulated.

7. A device for dispensing liquids, comprising a standard provided with a portion adapted to hold a liquid container or bottle in inverted position and provide an air chamber, an open ended chamber in said standard beneath the bottle-holding portion and provided with ports communicating with the bottle-holding portion, both of said ports being provided with extensions, the one adapted to extend into the neck of the inverted bottle, while the other is adapted to extend along the side of the bottle and above the orifice thereof to constitute an air inlet, said chamber being also provided with an outlet port, a hollow valve rotatably mounted in said chamber, provided with an open end and a pair of ports adapted to alternately register with the bottle or inlet port of the chamber and with the discharge port thereof and with an elongated air port adapted to constantly register with the air-inlet port of said chamber, means adapted to close the end of said chamber and of said valve, said means being provided with an open ended hollow stem extending into the valve, and a diaphragm in said hollow stem and adjustable from the inner end thereof, whereby the capacity of said valve is determined.
